Primary Examiner — Lauren R Calve(74) *Attorney, Agent, or Firm* — Hulsey P.C.(57) **CLAIM**

The ornamental design for a live herb grocery display package, as shown and described.

DESCRIPTION

FIG. 1 is a front perspective view of a live herb grocery display package showing our new design.

FIG. 2 is a top perspective view thereof.

FIG. 3 is a front view thereof.

FIG. 4 is a top view thereof; and,

FIG. 5 is a bottom view thereof.

In FIGS. 1-5 the broken lines having equal length segments represent stitching and form no part of the claimed design.

1 Claim, 2 Drawing Sheets(56)
